HELICAL ANTENNA SYSTEM

William Sichak, Lyndhurst, and James J. Nail, Basking Ridge, N. J., assignors to International Telephone and Telegraph Corporation, a corporation of Maryland

Application April 29, 1953, Serial No. 351,852

11 Claims. (Cl. 343—895)

This invention relates to helical antennas and more particularly to a helical antenna and tuning system for the same, capable of operating over an extremely wide frequency range.

In many applications, practical considerations require that the height of an antenna associated with a radio transmitter be very small when compared to the desired operating wavelength. Such conditions often arise in aerial radio system applications where the antenna must not only be small in physical size, have proper aerodynamic characteristics but must also be capable of operating over a wide frequency range. One common type of antenna utilized is a whip antenna which must be supported and fed through a base insulator. When such an antenna is short in length when compared to the operating wavelength there is a large voltage developed across the base insulator thereby introducing an appreciable loss of power in the base insulator. The helical antenna system as proposed allows an increase in the radiation resistance of 50% or more to be realized over a whip antenna for the same physical height but even more important is the fact that it allows the base insulator to be eliminated.

Heretofore helical antennas have been designed for operation over a wide frequency range. It is well known that such antennas are designed for quarter wave resonance at their lowest operating frequency and in order to operate over a wide frequency range it is necessary to electrically shorten the antenna. Various methods of electrically shortening helical antennas have been proposed such as means for physically decreasing the height of the radiator extending above a ground screen. Such an electrical shortening of the helical antenna by decreasing the height of the radiator extending above the ground plane has proven unsatisfactory and undesirable from the electrical standpoint since the antenna Q under such adjustment remains undesirably high over the entire frequency band. In addition, it has been usual in the past to vary the point of input coupling on the antenna. It has been found that providing a variable point of coupling creates many mechanical problems which in practice are difficult to solve.

One of the objects of this invention, therefore, is to provide a tuned helical antenna system having an optimum average bandwidth over a large frequency range.

Another object of this invention is to provide a tuned helical antenna system of relative high efficiency wherein the physical height of the radiator extended above the ground plane is maintained constant.

A further object of this invention is to provide a tuned helical antenna system which is mechanically easy and simple to construct.

A feature of this invention is the use of a helically shaped radiator extending above a ground plane conductor and having its base connected thereto. The center conductor of a coaxial feedline is connected to the helix in a manner to form a shunt feed. An adjustable shorting device varies the electrical length of the radi-

2

ator extending above the ground plane without varying the physical height of the antenna. The input coupling tap connection formed by the center conductor remains fixed with respect to the leading edge of the shorting device as the shorting device is adjusted to vary the operating frequency of the antenna.

The above-mentioned and other features and objects of this invention will become more apparent by reference to the following description taken in conjunction with the accompanying drawings, in which:

Fig. 1 is a longitudinal cross sectional view of one embodiment of a continuously tuned helical antenna system in accordance with the principles of this invention; and,

Fig. 2 is a longitudinal cross sectional view of another embodiment of the invention wherein the helical antenna system is capable of being tuned in finite steps.

Referring to Fig. 1 of the drawing, a continuously tuned helical antenna system is shown comprising a supporting structure 1 in the form of a cylinder composed of a low loss dielectric material such as fiberglass. A conductive element 2 is wound in the shape of a helical radiator 3 supported within and coaxially of the supporting cylinder 1. The helix 3 is designed to be resonant at the lowest operating frequency of the antenna system. The supporting cylinder 1 and helix 3 are supported by a ground plane conductor or screen 4. The lower end or base 5 of the helix 3 is grounded to the plane conductor 4. An electrical shorting device 6 extends through the ground plane 4 into and coaxially of the helix 3. The shorting device 6 comprises a threaded conductive cylinder 7 terminated at its upper end by a plurality of shorting fingers 8. To insure positive shorting of the portion of the helix 3 below fingers 8 the circumference of the shorting fingers 8 is made equal to one complete turn of the conductive element 2 forming helix 3. The threads 9 on the outer circumference of the shorting cylinder 7 have an outer diameter equal to the inner diameter of the helix 3 and the pitch of the threads 9 is equal to the pitch of helix 3. The design of the threads 9 insures positive contact between the shorting device 6 and the helix 3. The threaded cylinder 7 is supported by structure 10 comprising a conductive tube or nut connected to the ground plane conductor 4 and meshed with the threads 9 of device 6. Carried by and extending inside and coaxially of the cylinder 7 is a radio frequency feedline 11 comprising an inner conductor 12 and an outer conductor 13 separated by dielectric material 14. The outer conductor 13 is in electrical contact with and grounded by the cylinder 7. The inner conductor 12 extends beyond the upper limit of the shorting device 6 and fingers 8, terminating in a constant pressure wiping contact 15 for engagement with the helical conductor 2. The contact 15 is maintained a fixed distance from the shorting fingers 8. The lower end of the coaxial cable 11 terminates in a rotating joint 16. A feed-line 17 couples energy from a transmitter through joint 16 to the coaxial feedline 11 and thence to the antenna 3 through shunt feed 15.

At its lowest operating frequency the maximum height of the helix 3 must radiate or in other words the shorting fingers 8 of device 6 are in the lowest position contacting the conductive element 2 near the base 5 of helix 3. In order to tune the helical antenna for optimum efficiency at a higher frequency the shorting cylinder 7 together with the coaxial cable 11 are rotated causing the shorting fingers 8 to advance up the helix 3. As the shorting device 6 is rotated and advanced up the antenna the shunt feed 15 also advances maintaining a constant distance above the shorting fingers 8 which effectively shorts out all turns of the helix between the fingers 8 and the base 5 of the helix 3. As the operating frequency

of the antenna is increased the bandwidth of the antenna system is increased.

Referring to Fig. 2 of the drawing, another helical antenna system in accordance with the principles of this invention is shown which is capable of being tuned in finite steps and comprises a supporting structure 18 in the form of a low loss dielectric tube or cylinder. A conductive element 19 is wound in the shape of a helical radiator 20 around the outer circumference of tube 18. The helical antenna 20 is designed to be resonant at the lowest operating frequency of the antenna system. The supporting tube 18 and helix 20 are mounted on a portion 21 of ground plane conductor 22. Structural support for portion 21 is provided by a supporting post 23 which is coupled to the tube 18 and connected on its other end to supporting braces 24 and 25. The braces 24 and 25 are connected to the ground plane conductor 22. The lower end or brace 27 of the helix 20 is grounded via the metallic base 21, contacts 32, cylinder 29 and contact fingers 31. An electrical shorting device 28 extends through the ground plane 22 coaxially of the helix 20. The shorting device 28 comprises a conductive cylinder 29 terminated at its upper end by a plurality of shorting fingers 30 engaging the helix 20. To insure positive shorting of the portion of the helix 20 below the fingers 30 spring contacts 31 are provided between the ground plane 22 and cylinder 29 and contact is maintained between the metallic supporting structure 21 and cylinder 29 by means of contacts 32. A coaxial feedline 33 is rigidly coupled to the cylinder 29 by means of conductive brace 38 to which the outer conductor 36 of the feedline is connected. A brace 34 is terminated in a wiping contact 35 to couple the inner conductor 37 of coaxial feedline 33 as a shunt feed to the helix 20. The contact 35 is maintained a fixed distance from the shorting fingers 30. The feedline 33 couples energy from a transmitter (not shown) through contact 35 to the helix 20.

At its lowest operating frequency the maximum height of the antenna 20 must radiate or in other words the shorting fingers 30 of device 28 are in the lowest position contacting the conductive element 19 near the base 27 of the helix 20. In order to tune the helical antenna for optimum efficiency at a higher frequency, the shorting cylinder 29 together with coaxial feedline 33 are moved up the height of the cylinder causing shorting fingers 30 to electrically short out the lower turns of the helix 20. As the shorting device 28 advances up the height of the antenna the shun feed 35 is maintained a constant distance from the shorting fingers 30, thus effectively shorting out all turns of the helix 20 between the fingers 30 and the base 27. As the operating frequency of the antenna is increased the bandwidth of the antenna is increased. Since wiping contact 35 is advanced along the helix height one turn at a time the antenna shown in Fig. 2 can only be tuned in finite steps depending upon the pitch of the helix 20.

While we have described above the principles of our invention in connection with specific apparatus, it is to be clearly understood that this description is made only by way of example and not as a limitation to the scope of my invention as set forth in the objects thereof and in the accompanying claims.

We claim:

1. A radio antenna system comprising a conductive element disposed in the form of a helical radiator, means to couple radio frequency energy to said helical radiator, means adjustable to short out portions of said helical radiator to thereby change the effective electrical length of said radiator for resonance at different radio frequencies, and means to maintain the position of said coupling means a given distance from said adjustable shorting means.

2. A radio antenna system comprising a ground plane conductor, a conductive element having one end coupled to said ground plane conductor disposed in the form of

4
a helical radiator extending a given height above said ground plane conductor, adjustable means coupled to said ground plane conductor to effectively short out selected portions of said helical radiator in order to adjust the effective electrical length of said radiator for resonance at different radio frequencies and means to couple radio frequency energy to said radiator at a predetermined distance above said adjustable shorting means.

3. A radio antenna system comprising a conductive element disposed in the form of a helical radiator extending a given distance above ground, means to couple energy from a radio frequency source at desired frequencies within a relatively broad frequency range to said helical radiator, said coupling means including a coaxial transmission line having its outer conductor grounded, a coupling element coupled to the inner conductor of said line and to said helical radiator, means to adjust the effective electrical length of said radiator to render said helical radiator resonant at a desired frequency, and means to vary said coupling element relative to the turns of said helical radiator to maintain said coupling element in a predetermined relationship to said adjusting means.

4. A radio antenna system comprising a dielectric supporting structure, a conductive element disposed in the form of a helix supported by said structure, means to adjust the effective electrical length of said radiator to cause a portion of said helical radiator to resonate at a desired frequency, and means to couple energy at said radio frequency to said helical radiator at a predetermined distance from said adjustable means.

5. A radio antenna system comprising a ground plane conductor, a dielectric supporting structure, a conductive element having one end coupled to said ground plane conductor disposed in the form of a helical radiator supported by said dielectric structure extending above said ground plane conductor, adjustable means coupled to said ground plane conductor to short out portions of said helical radiator to thereby change the effective electrical length of said radiator for resonance at different radio frequencies, a coaxial transmission line carried by said adjustable means having an outer conductor grounded and an inner conductor with one end thereof coupled to a source of radio frequency energy, and means to cause the second end of said inner conductor to couple energy to a portion of said helix at a given distance from said adjustable shorting means.

6. A radio antenna system comprising a ground plane conductor, a dielectric supporting structure of cylindrical shape carried by said ground plane conductor, a conductive element having one end coupled to said ground plane conductor disposed in the form of a helical radiator around said supporting structure, a conductive cylinder grounded to said ground plane conductor and adjustably movably along the axis of said helical radiator, a plurality of contacts mounted on one end of said cylinder to electrically couple said conductive cylinder to said helical radiator to short out portions of said helical radiator to thereby change the effective electrical length of said radiator for resonance, a coaxial transmission line carried by said conductive cylinder having an outer conductor coupled to said ground plane conductor and an inner conductor with one end thereof coupled to a source of radio frequency energy, and means to cause the second end of said inner conductor to couple energy to a portion of said helix at a given distance above said cylinder mounted contacts.

7. A radio antenna system comprising a ground plane conductor, a dielectric supporting structure of hollow cylindrical shape, a conductive element having one end coupled to said ground plane conductor disposed in the form of a helical radiator supported by and inside said dielectric structure extending above said ground plane conductor, adjustable means coupled to said ground plane conductor to short out portions of said helical radiator to thereby change the effective electrical lengths of said

radiator for resonance, a coaxial transmission line carried by said adjustable means having an outer conductor grounded and an inner conductor with one end thereof coupled to a source of radio frequency energy, and means to cause the second end of said inner conductor to couple energy to a portion of said helix at a given distance above said adjustable shorting means.

8. A system according to claim 7 which further includes a rotating joint, said coaxial transmission line being coupled to said radio frequency energy through said 10 rotating joint.

9. A system according to claim 7 wherein said adjustable shorting means comprises a threaded conductive cylinder having an outside thread diameter equal to the inner diameter of said helix.

10. A system according to claim 9 wherein said con-

ductive cylinder is terminated by a plurality of conductive spring fingers, said plurality of spring fingers having a circumference equal to the circumference of said helix whereby one complete turn of said helical radiator may be shorted to said conductive cylinder.

11. A device according to claim 9 wherein the pitch of said threads on said conductive cylinder is substantially equal to the pitch of said helical radiator.
